UNITED STATES PATENT OFFICE.

ARTHUR P. PINKLER, OF WATERBURY, CONNECTICUT, ASSIGNOR TO THE BRISTOL COMPANY, OF WATERBURY, CONNECTICUT, A CORPORATION OF CONNECTICUT.

ELECTRICAL LOUD-SPEAKING RECEIVER.

Application filed August 23, 1921. Serial No. 494,697.

To all whom it may concern:

Be it known that I, ARTHUR P. PINKLER, a citizen of the United States, and a resident of Waterbury, in the county of New Haven and State of Connecticut, have invented certain new and useful Improvements in Electrical Loud-Speaking Receivers, of which the following is a specification.

10 The invention relates to electrical receiver apparatus for amplifying sounds, such receiver device being generally termed "Loud speaking receivers".

It is the object of the invention to provide 15 a compact, ruggedly constructed receiver device of this character and one which shall be comparatively light and of low power consumption and in which the arrangement of parts is such, moreover, that undesirable 20 vibrations are obviated, the active parts being simple, light and free to respond.

The nature of the invention will, however, best be understood when described in connection with the accompanying drawing, in 25 which—

Fig. 1 is a longitudinal section thru the receiver device.

Fig. 2 is a horizontal section taken on the line 2—2, Fig. 1, looking in the direction of 30 the arrows.

Fig. 3 is a transverse section taken on the line 3—3, Fig. 1, looking in the direction of the arrows.

Similar characters of reference designate 35 corresponding parts thruout the several views.

Referring to the drawings, 10 designates a suitable casing or container wherein the entire apparatus may conveniently be 40 mounted and housed. The device itself comprises a permanent U-shape magnet 11, one leg being shorter than the other and having pole pieces 12 and 13 directed at right angles from the ends thereof. The 45 pole piece 13, furthermore, is provided with a solenoid 14 thru which current passes, as received from a transmitting apparatus (not shown) and as is well understood. Suitable leads 15 are connected to the said solenoid 50 for this purpose.

The magnet 11, in addition, carries a sound box 16 which is adjustably secured thereto for slight angular motion, the adjustment being effected, for example, thru suitable nuts 17 working on the screw 18.

A nut 19 serves to secure the sound box and attached magnet to the cover of the casing 10; and an outlet 20 extends thru the said cover and may receive a suitable horn 21 or other amplifying member. 60

In order to effect the amplification, the diaphragm 22 of the sound box is to be vibrated in accordance with pulsations received from the transmitting circuit 15 in which electrical impulses have been greatly 65 strengthened by the introduction of a local battery (not shown); and their increased effect is to be delivered to the solenoid 14, all of which is well understood and forms no 70 part of the present invention. However, in accordance with the invention, the effect of these pulsations on the magnetic attraction of the pole piece 13 is conveyed to the diaphragm 22 in a most direct and positive manner; and, for this purpose, a free one-piece lever 23 is provided and is mounted 75 therebetween, said lever being preferably provided with a stamped-out lateral rib 23'. For example, at its one end, it is positively 80 attached in any well-known or special manner to the center of the diaphragm 22 and at its other end it carries an armature 24 in proximity to the end of the pole piece 13 so as to be influenced thereby and vibrated in accordance with pulsations of current pre- 85 vailing in the solenoid. Lever 23, moreover, is fulcrumed on the other pole piece, merely resting thereon; and, preferably, is guided against lateral displacement as by means of a pin 25 extending from the pole piece 12 90 and fitting into a groove 26 of the lever.

In this manner, a direct and positive multiplying connection is afforded by a single part; and thus obviates any extraneous and undesirable vibrations such as occur when 95 the usual intricate system of levers and joints is involved. The adjustment of the sound box as a whole to vary the air gap between the armature 24 and pole piece 13 affords, moreover, means for delicately adjusting the apparatus. The apparatus, furthermore, while of the utmost simplicity is also extremely compact and of rugged construction so that it is not likely readily to get out of order even with rough usage. As 100 a consequence, the amplification afforded by the device is of a high degree, for example, a ratio of diaphragm movement to armature movement of four to one; and the reproduction is of high quality. 110

I claim:—

An electrical loud speaking receiver, comprising a permanent magnet having two pole pieces, a sound box adjustable relative-
5 ly thereto and provided with a diaphragm, a one-piece lever provided with a lateral rib and positively attached at the one end to said diaphragm and magnetically held between its ends to one of said pole pieces,

the opposite end of said lever being free and 10 carrying an armature under the influence of the other of said pole pieces, and means to vary the attraction of the last-named pole piece for the said armature.

Signed at Waterbury, in the county of 15
New Haven and State of Connecticut this
20th day of August A. D., 1921.

ARTHUR P. PINKLER.
